UNITED STATES PATENT OFFICE.

GEORGE WILLIAM BENJAMIN CREEES, OF WINGFIELD, COUNTY OF WILTS,
ENGLAND.

MACHINE FOR WASHING DISHES, &c.

SPECIFICATION forming part of Letters Patent No. 397,783, dated February 12, 1889.

Application filed April 21, 1888. Serial No. 271,449. (No model.) Patented in England June 17, 1887, No. 8,720, and in France May 9, 1888, No. 190,509.

To all whom it may concern:

Be it known that I, GEORGE WILLIAM BENJAMIN CREEES, engineer, of Wingfield, in the county of Wilts, England, have invented certain new and useful Improvements in Machines for Washing Plates, Dishes, and other Similar Articles, (for which Letters Patent were granted to me heretofore by the governments of Great Britain, No. 8,720 of 1887, dated 5 June 17, and of France, No. 190,509, dated May 9, 1888,) of which the following is a specification.

My invention relates to improvements in machinery for washing plates, dishes, and similar articles.

In describing my invention I refer to the accompanying drawings on Sheets 1 to 4, and to the figures and letters of reference thereon.

On Sheet 1 Figure 1 represents a side elevation of my apparatus. On Sheet 2 Fig. 2 represents an elevation of the same on the reverse side. On Sheet 3 Fig. 3 represents a central longitudinal section of the apparatus. On Sheet 4 Fig. 4 represents a central vertical transverse section of the machine.

I provide a suitable box or receptacle, A, to hold water or liquid, either hot or cold, and the supply and discharge of this might be continuous, it passing through the box or receptacle, if deemed desirable. In the box or receptacle A, I mount brushes B B' on suitable spindles running in stuffing-boxes C C', fixed on the sides of the box or receptacle A. These spindles carry spur-wheels D D', gearing one into the other, whereby the brushes rotate in opposite directions. On the spindle of D', I mount a pinion, E, rigidly keyed thereto, and which gears into a spur-wheel, F, mounted on the driving-shaft G of the machine, which may be driven by hand, treadle, or from a suitable motor. As shown, a fly-wheel is fitted on the shaft for handle or treadle operation.

The shaft G carries on the opposite side of the box or receptacle a pinion, H, gearing with an idle-pinion, I, which drives a large spur-wheel, J, for the purpose hereinafter described.

In the box or receptacle A, I provide guides—such as K L—suitably fixed to the

box or receptacle, as by brackets M N, secured to the same. The guides K L extend downward and between the brushes, as shown.

The box A is provided on opposite sides with vertical guides P Q, as shown in Fig. 4. 55 A dish-carrying frame, O, reciprocates between the guides K L and P Q. A rod, R, connects this frame with a cross-head, S, which slides vertically on an upright standard, T, attached to the box A. On the outer end of 60 the cross-head S is pivoted a link, U, connected by pivoted joint to crank V, carried from spur-wheel J. By the revolutions of this wheel the cross-head rises and falls on the fixed rod or standard T, so working the frame O up and 65 down. An oscillatory lever, X, is pivoted at Y to the lower end of the box, and extends upward at one side thereof to a point above the top of the box. This lever is provided at its upper end with a plate, Z, and at its lower 70 bent end with a weight, which tends to swing the lever into contact with the cam-arm W on the crank V. This cam-arm W serves to push out the lever as the cam is rotated. The lever X carries a pin, a, running in a segmental 75 slot, b, suitably affixed to the machine. c is a fixed guide-plate for use in feeding the plates, dishes, or similar articles into the machine. Both plate Z and fixed guide-plate c may be padded with rubber or other soft or elastic 80 material, if required.

e d are boxes or sinks to contain, respectively, the dirty articles to be washed and the final rinsing-water.

The frame O, before mentioned, is clearly 85 shown in Figs. 3 and 4, and is carried to a convenient distance across and down into the box or receptacle A, and will consequently rise and descend therein, and is so placed that it does not interfere with the action of 90 the rotating brushes while in motion. Arms f project upward from the lower bar, g, of the dish-carrying frame O, and serve to support the dish at their upper ends while being washed.

In working the machine the action is as follows: The plate, dish, or similar article to be cleansed is placed on the fixed guide-plate c and the machine started. The plate Z then retreats, owing to the curved arm or cam end 100

W, carried on the crank V, pushing back the same as the wheel J rotates. The plate, dish, or other article then descends between the brushes B B' and guides K L, resting eventually on the arms or projections f f, carried by the cross-bar g on the frame O, which may be padded, if desired. As the machine is further operated, the frame O rises, carrying with it on the arms or projections f f the plate, dish, or other similar article. The plate Z has in the meantime advanced toward the fixed guide-plate c, and as the plate, dish, or other article is lifted by the frame O and its arms or projections f f it slips under the moving plate Z and is delivered upon the sloping platform h, when it can glide into the rinsing-tank d, filled with water or cleansing-liquid. It can then be lifted out and dried, as usual. Another plate, dish, or similar article is then placed against the fixed guide-plate c and the moving plate Z, which, retreating, allows the article to descend between the brushes to be raised and delivered.

If desired, fixed brushes might be used, but this plan is inferior.

Having now particularly described and ascertained the nature of my said invention

and in what manner the same is to be performed, I declare that what I claim is—

1. In a machine for washing dishes, the combination of a box, rotary brushes supported therein, guides in said box, a dish-frame movable in said guide, and means for reciprocating said frame.
2. In a machine for washing plates, dishes, or similar articles, the combination of fixed guides such as K L, rotating brushes, such as B B', mounted in a washing trough or receptacle, reciprocating frame, such as O, fixed guide, such as c, and traveling-plate, such as Z, substantially as and for the purposes described.

In testimony that I claim the foregoing as my invention I have signed my name in presence of two subscribing witnesses.

GEORGE WILLIAM BENJAMIN CREESE.
